UNITED STATES PATENT OFFICE.

WALTER N. BEECHER, OF CHICAGO, ILLINOIS.

WIND-SHIELD FOR VEHICLES.

No. 902,199.

Specification of Letters Patent.

Patented Oct. 27, 1908.

Application filed January 13, 1908. Serial No. 410,605.

To all whom it may concern:

Be it known that I, WALTER N. BEECHER, a citizen of the United States, and a resident of Chicago, in the county of Cook and State of Illinois, have invented certain new and useful Improvements in Wind-Shields for Vehicles, of which the following is a full, clear, and exact description.

My invention relates to wind-shields for vehicles, such, for example, as automobiles, and its object is to provide a divided or "split" wind-shield consisting of an upper and a lower sash the former being preferably hinged to the latter so that it can be lowered in front of the same when so desired.

Another object is to provide suitable means for preventing the accidental lowering of the upper sash owing to the loosening of the clamping-bolt, as is sometimes caused by the vibration of the vehicle on rough roads.

This I accomplish in the manner herein-after fully described and as more particularly pointed out in the claims.

In the drawings:—Figure 1 is a side elevation of a fragmental portion of the forward end of an automobile showing my improved wind-shield attached thereto; Fig. 2 is an enlarged detail of the adjusting bracket used in connection therewith. Fig. 3 is a transverse horizontal section thereof taken on dotted line 3—3, Fig. 2 looking in the direction indicated by the arrows, and Fig. 4 is a detached perspective view of the hinge and the pivoted bolt employed in connection therewith.

Referring to the drawings, 1 represents the bonnet or hood, surrounding and inclosing the engine or other motive power for propelling the vehicle, and which is usually supported on the forward ends of the side-sills 2 of the vehicle. Suitably fitted on the rear end of the bonnet and extending above the same a short distance is the lower section 3 of a wind-shield that comprises a frame-work, preferably made of metal or wood surrounding a rectangular plate of glass. An upper section 4 comprising a frame inclosing glass of approximately the same proportions as that in the lower sash and is secured along its lower edge to the upper edge of said lower section by means of suitable hinge-plates 5, 5.

Secured to the upper portion of the stiles of the lower section 3 and, preferably, ex-

tending half above and half below the horizontal dividing line between the sections 3 and 4, are two corresponding substantially D-shaped brackets 6, 6. These brackets are provided with supporting plates α projecting at right angles to the rear edges of their vertical portions, the lower half of each of which is secured by screws or otherwise to the rear of the stiles of the lower sash in such position that their upper halves extend above the upper edge of said sash. The forwardly projecting semi-circular part 7 of each bracket has a segmental slot 8 cut therein parallel with the curved edges thereof, and this slot extends across the vertical portion of the bracket and into the angular supporting-plate where it meets a recess 17 cut in the edge of said supporting-plate. At a suitable point this semi-circular portion 7 is provided with a forwardly and downwardly projecting screw-threaded stud 9 onto which the brace-rod 10 is screwed. The forward and lower end of this brace is secured to the forward ends of the side-sills 2 of the body by bolts or rivets, substantially as shown.

The backs of the upper plates of the hinges are each provided with a pair of laterally projecting parallel pivot lugs 11, 11, that extend horizontally to the rear thereof, and fit into a recess or niche 12 cut in the lower side edges of the stiles of the upper sash. A screw-threaded locking bolt 13 having its inner end provided with an enlarged head 14 is secured between these lugs 11, by means of a pintle 15, which is tapped through said parts so that said bolt can be swung on its pivot in a plane transverse to said sash. This bolt is so arranged that its outer end projects through the segmental slot 8 in the bracket, and has a hand-nut 16 screwed thereon in order that, when the upper sash is being swung down, said bolt moves in the segmental slot until it reaches the lower end thereof, whereupon if the hand-nut is then tightened, said upper sash will be locked in its lowered position. When, however, it is desired to raise the wind-shield to its full height the hand-nut is loosened and the upper sash is swung upward causing the bolt to move in the segmental slot until the frame of the upper sash abuts against the supporting-plate of the upper portion of the bracket. The bolt is then swung on its pintle around the corner of said bracket in which position its shank will enter the recess 17, whereupon by tightening the hand-nut 16, the upper

sash will be locked to the lower sash in the raised position. This so firmly locks the upper sash that it will prevent it from accidentally falling forward even though said hand-nut should become loosened by the vibration of the vehicle, and will prevent it from lowering until the bolt is swung on its pivot around the corner of the bracket into the segmental slot again.

10. What I claim as new is:—

1. A wind-shield for vehicles comprising a stationary lower sash and a movable upper sash hinged thereto, a bracket secured to and projecting above the top edge of the lower sash and provided with a transverse recess near the upper end of its vertical portion, and a swinging pivoted bolt secured to said upper sash and adapted to engage said recess and lock said upper sash in its adjusted position.

2. A wind-shield for vehicles comprising a stationary lower sash and a movable upper sash hinged thereto, a bracket secured to and projecting above the top edge of the lower sash and provided with a transverse recess near the upper end of its vertical portion, a swinging pivoted bolt secured to said upper sash and adapted to enter said recess when said sash is raised, and a hand-nut engaging said bolt the tightening of which secures said upper sash in its adjusted position.

3. A wind-shield for vehicles comprising a stationary lower sash and a movable upper sash hinged thereto, a bracket secured to and projecting above the upper portion of the lower sash and having a semi-circular slot therein that connects with a transverse recess in the vertical portion of said bracket, and a pivoted bolt secured to the upper sash and operating in said slot and adapted to engage said recess and lock said upper sash in its adjusted position.

4. A wind-shield for vehicles comprising a stationary lower sash and a movable upper sash hinged thereto, a bracket secured to and projecting above the upper portion of the lower sash and having a semi-circular slot therein that connects with a transverse recess in the vertical portion of said bracket, a pivoted bolt operating in said slot secured to said upper sash and adapted to be seated in said recess, and a hand-nut engaging said bolt the tightening of which secures said upper sash in its adjusted position.

5. A wind-shield for vehicles comprising a stationary lower sash and a movable upper sash, hinges connecting the same, the plate thereof attached to the upper sash having parallel lugs projecting laterally therefrom, a bracket secured to and projecting above the top edge of the lower sash and provided with a transverse recess near the upper end of its vertical portion, and a bolt one end of which is pivotally secured between the lugs on said hinge-plate and the free end

thereof is adapted to enter said recess and lock said upper sash in its adjusted position.

6. A wind-shield for vehicles comprising a stationary lower sash and a movable upper sash, hinges connecting the same, the plates thereof attached to the upper sash having parallel lugs projecting laterally therefrom, a bracket secured to and projecting above the top edge of the lower sash and provided with a transverse recess near the upper end of its vertical portion, a bolt one end of which is pivotally secured between the lugs on said hinge-plate and the free end thereof is adapted to enter said recess when said sash is raised, and a hand-nut engaging said bolt the tightening of which secures said upper sash in its adjusted position.

7. A wind-shield for vehicles comprising a stationary lower sash and a movable upper sash, hinges connecting the same the plate thereof attached to the upper sash having parallel lugs projecting laterally therefrom, a bracket secured to and projecting above the top edge of the lower sash and provided with a transverse recess near the upper end of its vertical portion, a brace the upper end of which is secured to said bracket and the lower end to the body of the vehicle, and a bolt one end of which is pivotally secured between the lugs on said hinge-plate and the free end thereof is adapted to enter said recess and lock said upper sash in its adjusted position.

8. A wind-shield for vehicles comprising a stationary lower-sash, and a movable upper sash, hinges connecting the same the plate thereof attached to the upper sash having lugs projecting laterally therefrom, a bracket secured to and projecting above the upper portion of the lower sash provided with a transverse recess near the upper end of its vertical portion, and having a semi-circular slot therein that connects with said recess, and a bolt one end of which is pivotally secured between the lugs on said hinge-plate and the free end thereof is movable in said slot and adapted to engage said transverse recess and lock the upper sash in a raised position.

9. A wind-shield for vehicles comprising a stationary lower sash and a movable upper sash, hinges connecting the same the plate thereof attached to the upper sash having lugs projecting laterally therefrom, a bracket secured to and projecting above the upper portion of the lower sash provided with a transverse recess near the upper end of its vertical portion, and having a semi-circular slot therein that connects with said recess, a bolt one end of which is pivotally secured between the lugs on said hinge-plate and the free end thereof is movable in said slot and adapted to engage said transverse recess when the upper sash is in a raised position, and a hand-nut engaging said bolt the tight-

ening of which locks said upper sash in its adjusted position.

10. A wind-shield for vehicles comprising a stationary lower sash and a movable upper sash hinged thereto, a bracket comprising a vertical angle-plate adapted to be secured to the upper end of the stile of said lower sash so that a portion thereof projects above the upper edge of said sash, and having a slot 5 therein that extends around the angle thereof and means adapted to engage the portion of said slot on one side of said angle when the sash is in one position and the portion of said slot in the other side of said angle when 15 the sash is in another position.

11. A wind-shield for vehicles comprising a stationary lower sash and a movable upper sash hinged thereto, a bracket comprising a vertical angle-plate adapted to be secured 20 to the upper end of the stile of said lower sash so that a portion thereof projects above the upper edge of said sash, and having a slot therein that extends around the angle thereof and a bolt adapted to engage the 25 portion of said slot on one side of said angle when the sash is in one position and the portion of said slot on the other side of said angle, when the sash is in another position.

12. A wind-shield for vehicles comprising 30 a stationary lower sash and a movable upper sash hinged thereto, a bracket comprising a vertical angle plate adapted to be secured to the upper end of the stile of said lower sash so that a portion thereof projects above 35 the upper edge of said sash, and having a

slot therein that extends around the angle thereof and a pivoted bolt adapted to engage the portion of said slot on one side of said angle when the sash is in one position and the portion of said slot on the other side of 40 said angle when the sash is in another position.

13. A wind-shield for vehicles comprising a stationary lower sash and a movable upper sash hinged thereto, an angular bracket secured to and projecting above the top edge 45 of the lower sash and provided with a transverse slot extending around the angle of the same, and means secured to the upper sash and adapted to engage said slot and move 50 around the angle of said bracket when said upper sash is in a raised position.

14. A wind-shield for vehicles comprising a stationary lower sash and a movable upper sash hinged thereto, an angular bracket secured to and projecting above the top edge 55 of the lower sash and provided with a transverse slot extending around the angle of the same, and a pivoted bolt secured to the upper sash and adapted to engage said slot and 60 move around the angle of said bracket when said upper sash is in a raised position.

In testimony whereof I have hereunto set my hand and seal this 31st day of December, A. D., 1907.
